Specification for Design.

Patented Feb. 21, 1922.

Application filed March 11, 1921. Serial No. 451,580. Term of patent 3½ years.

To all whom it may concern:

Be it known that I, JOSEPH RIZZI, a citizen of the United States, residing at Weehawken, in the county of Hudson and State of New Jersey, have invented a new, original, and ornamental Design for Lace, of which the following is a specification, reference being had to the accompanying drawing, forming part thereof.

The figure is a face view of lace, showing my new design.

I claim:

The ornamental design for lace, as shown.

JOSEPH RIZZI.
